(No Model.)

T. JAMES.

FURNACE DRAWING AND CHARGING APPARATUS.

No. 479,883.

Patented Aug. 2, 1892.

Thomas James
by W. Baxendell & Sons
his Attorneys

UNITED STATES PATENT OFFICE.

THOMAS JAMES, OF BRADDOCK, PENNSYLVANIA.

FURNACE DRAWING AND CHARGING APPARATUS.

SPECIFICATION forming part of Letters Patent No. 479,883, dated August 2, 1892.

Application filed October 20, 1891. Serial No. 409,285. (No model.)

To all whom it may concern:

Be it known that I, THOMAS JAMES, of Brad-
dock, in the county of Allegheny and State of
Pennsylvania, have invented a new and use-
5 ful Improvement in Furnace Drawing and
Charging Apparatus, of which the following
is a full, clear, and exact description.

The object of my invention is to provide
tongs for furnace charging and drawing ap-
10 paratus which shall be simple and rapid in
action and not apt to get out of order. It is
illustrated in the accompanying drawings,
forming part of this specification, in which—

Figure 1 shows the tongs in plan view, the
15 operating mechanism being in horizontal lon-
gitudinal section on the line I I of Fig. 2.
Fig. 2 is a side elevation of the tongs and their
operating mechanism. Fig. 3 is a view simi-
20 lar to Fig. 1, showing, on an enlarged scale, the
tongs when open. Fig. 4 is an enlarged side
elevation of the tongs and trolley.

In the drawings, 2 represents a beam or car-
rier by which the tongs are supported and by
25 which they are carried to and from the fur-
nace. This carrier may form part of an ordi-
nary charging - crane, whose construction
should be such as to suit the requirements of
the particular use to which it is put.

3 is a cylinder, which is fixed to the carrier
30 and is carried thereby. The piston 4 of this
cylinder has a hollow projecting piston-rod 5,
the forward end of which is fixed to and com-
municates with a small tongs-operating cylin-
35 dier 6, having a piston 7 and forwardly-pro-
jecting piston-rod. The latter cylinder and
the frame 9 of the tongs are supported by a
trolley 8 from the carrier 2 and are capable
40 of longitudinal motion thereon by operation
of the piston of the cylinder 3. The tongs
comprise two jaws 10, which are pivotally con-
nected by a pin 11 and have rearwardly-pro-
jecting arms 12, which at their extremities
45 are connected by toggle links or levers 13, the
middle joint of which is pivotally connected
to the piston-rod of the tongs-operating cyl-
inder 6.

14 is a rod, which projects longitudinally
between the jaws of the tongs and is provided
with a slot, which fits around the pin 11 and
50 permits longitudinal motion of the rod. This
rod may be removed when the apparatus is
employed in charging the furnace.

15 is a valve, which controls the admission
and exhaust of motive fluid to the cylinder 6
and is adapted to be reciprocated to control 55
the action of the cylinder by means of a stem
16, lever 17, and rod 18, which latter is con-
nected with the rod 14 by an interposed com-
pressible spring 19. The valve 15 controls
three ports 20, 21, and 22, of which the port 60
20 leads to the valve-chest from the hollow
piston-rod 5. The ports 21 and 22 lead from
the valve-chest to the front and back ends of
the cylinder, respectively. The exhaust-port
65 leads from the valve-chest outside the path of
the slide-valve and is not shown. The motive
fluid (preferably steam) for the cylinder 6 is
supplied by a pipe 23, which extends axially
70 through the cylinder 3 and through the pis-
ton 4 telescopically into the piston-rod 5, so
that communication between the cylinder 6
and the supply-pipe 23 is maintained in every
position of the apparatus. The valve-stem
75 16 has a rearward projection and is provided
with a tappet-lever 24, the end of which is
so situate as to be adapted to engage a stop-
rod 25 on backward motion of the tongs-
frame. To cushion the action of the rod 25,
I prefer to set it in slide-bearings 26, in which
80 it is capable of longitudinal movement, and
to connect it by a bell-crank lever 27 and
chain 30 with a weighted piston 28, set in a
dash-pot 29.

The operation of the apparatus is as fol-
lows: Suppose that it be desired to use the 85
tongs to grasp and withdraw an ingot or bloom
31, lying on the hearth of a furnace. The
carrier is first brought into position opposite
to the door of the furnace, and then by ad-
mitting motive fluid to the rear end of the 90
cylinder 3 the trolley 8, carrying the tongs
and the cylinder 6, is projected on the carrier.
The tongs enter the furnace-door, and their
jaws being then open, as indicated by dotted
lines in Fig. 1, pass on opposite sides of the 95
end portion of the ingot or bloom. As the
tongs continue to advance, the end of the rod
14 engages the end of the ingot or bloom and
is pushed back thereby, transmitting through
the spring 19, rod 18, and lever 17 motion to 100
the valve-stem 16, shifting the valve so as to
connect the steam-admission port with the
forward end of the cylinder 6. The effect of
this is to retract the piston 7, thus straight-

ening the toggle-links 13, spreading the arms 12 of the tongs, and closing their jaws upon the interposed ingot or bloom, which they grasp firmly, as shown in Fig. 1. The piston 5 of the cylinder 3 may then be reversed, so as to retract the tongs and to draw the ingot or bloom from the furnace. When they have reached a predetermined point, the end of the tappet-lever 24 engages the end of the rod 25, 10 and is thereby moved, so as to shift the valve-stem and to move the valve sufficiently to connect the rear end of the cylinder 6 with the fluid-supply port. The piston 7 is thereupon projected, and, acting on the middle 15 joint of the toggle-links 13, moves them into inclined position, thus drawing together the arms 12, spreading the jaws 10, and releasing the ingot or bloom, (see Fig. 3,) which then should be in position over a car or other convenient receiving support.

It will be understood that my improved device may be modified in construction in divers ways without departing from the principles of my invention as stated in the following claims. Thus, instead of employing the ingot or bloom as the stop which operates the valve on the forward motion of the apparatus, I may use some other stop fixed to the furnace or otherwise and designed to 25 form a like function.

I claim—

1. In furnace charging or drawing apparatus, the combination of tongs adapted to grasp an ingot or bloom, a power-cylinder connected 35 with the tongs and adapted to operate the same, a valve controlling said cylinder, and a stop whereby on motion of the apparatus the valve is engaged and shifted to operate the cylinder, substantially as and for the purposes 40 described.

2. In furnace charging or drawing apparatus, the combination of tongs adapted to grasp an ingot or bloom, a power-cylinder connected with the tongs and adapted to operate the 45 same, a valve controlling said cylinder, a stop whereby on forward motion of the apparatus the valve is engaged and shifted, and a second stop whereby the valve is engaged on

rearward motion of the apparatus, substantially as and for the purposes described. 50

3. In furnace charging or drawing apparatus, the combination of tongs adapted to grasp an ingot or bloom, a power-cylinder connected with the tongs and adapted to operate the same, a valve controlling said cylinder, and a 55 rod connected with the valve and adapted to engage the ingot or bloom to be seized, substantially as and for the purposes described.

4. In furnace charging or drawing apparatus, the combination of tongs adapted to grasp an ingot or bloom, a power-cylinder connected 60 with the tongs and adapted to operate the same, a valve controlling said cylinder, a rod connected with the valve and adapted to engage the ingot to be seized, and an interposed 65 spring, substantially as and for the purposes described.

5. In furnace charging or drawing apparatus, the combination of tongs adapted to grasp an ingot or bloom, a power-cylinder connected 70 with the tongs and adapted to operate the same, a valve controlling said cylinder, a stop whereby on forward motion of the apparatus the valve is engaged and shifted, a second stop whereby the valve is engaged on rear- 75 ward motion of the apparatus, and a cushion for the second stop, substantially as and for the purposes described.

6. In furnace charging or drawing apparatus, the combination of tongs adapted to grasp an ingot or bloom, a power-cylinder connected 80 with the tongs and adapted to operate them, a cylinder connected with the tongs and adapted to project them, a hollow piston-rod for the last-named cylinder, and a motive-fluid- 85 supply pipe extending telescopically into the piston-rod and connected by the latter with the tongs-operating cylinder, substantially as and for the purposes described.

In testimony whereof I have hereunto set 90 my hand this 17th day of October, A. D. 1891.

THOMAS JAMES.
